(57) CLAIM

The ornamental design for a brush, as shown and described.

DESCRIPTION

FIG. 1 is a front, top, and right side perspective view of a brush;

FIG. 2 is a front elevational view of the brush of FIG. 1; FIG. 3 is a rear elevational view of the brush of FIG. 1; FIG. 4 is a right side elevational view of the brush of FIG. 1;

FIG. 5 is a left side elevational view of the brush of FIG. 1; FIG. 6 is a top plan view of the brush of FIG. 1;

FIG. 7 is a bottom plan view of the brush of FIG. 1; and, FIG. 8 is a perspective view of a front, bottom, and right side of the brush of FIG. 1.

The dash-dash-dash lines are included for the purpose of illustrating portions of the brush that form no part of the claimed design.

1 Claim, 8 Drawing Sheets
